Wm H. Campfield,
ATTORNEY.

UNITED STATES PATENT OFFICE.

MARCUS PATTERSON, OF BROOKLYN, NEW YORK.

STRIP FOR FLOOR COVERINGS AND THE LIKE.

1,423,143.

Specification of Letters Patent.

Patented July 18, 1922.

Application filed January 30, 1922. Serial No. 532,748.

To all whom it may concern:

Be it known that I, MARCUS PATTERSON, a citizen of the United States, and a resident of Brooklyn, county of Kings, and State of 5 New York, have invented certain new and useful Improvements in Strips for Floor Coverings and the like, of which the following is a specification.

This invention relates to an improved 10 strip adapted for various purposes, but particularly designed for holding down floor coverings, especially linoleum and oil cloth.

The strip is arranged at the edge of the linoleum and thus covers any inequalities in 15 cutting, and also acts as a closure so that water and dirt do not seep down between the linoleum and the floor.

The strip also provides a secure holding 20 means so that curling and warping of the edges of the linoleum are prevented, and furthermore, it is easily and quickly laid and is adapted for cheap manufacture.

The invention is illustrated in the accompanying drawing, in which Figure 1 is 25 a perspective view of a strip made according to my invention, and Figure 2 is a section of the strip, showing it in position on the floor. Figure 3 is a section of a modified form of construction. Figure 4 is a section 30 of the strip shown in Figure 1, but slightly modified. Figure 5 is a section of a still further modified form, and Figure 6 is a perspective view of another form of strip.

The strip 10, shown in Figure 1, is provided on one edge with a flap 11 that extends longitudinally along the strip and projects from the top edge of the strip and is adapted, as will be seen from Figure 2, to fit down on the top face of the linoleum near 40 the edge of it, the portion under the flap providing an under-cut part to receive the edge of the linoleum 12 and thus being adapted to hold it down, providing a good appearance and forming a closure, since the 45 flap is preferably made of resilient material, the whole strip being usually made of rubber or similar substance which has a degree of flexibility which permits it to be turned into corners and to fit around projecting 50 parts in a room.

The other edge of the strip is under-cut by forming the face 13 in a downwardly and inwardly inclined direction so that this edge forms an upwardly inclined pointed ridge 55 14 on the top edge, so that any upward ten-

dency of the floor covering 12 will cause the ridge 14 to "bite" and thus be frictionally engaged by the side wall 15, so that the strip will not be raised and the linoleum will be held down.

In order to allow for many different thicknesses of material, from oil cloth to thick linoleum, the flap can be made so that it normally inclines rather sharply downwardly away from the strip, as shown in 65 Figure 4.

When laying linoleum at present it is very often done by means of a substance which in the trade is known as cement, which is laid on the floor and then the linoleum is 70 pressed to it and the cement is an adhesive. In the present device the adhesive can be used to hold down the strip, thereby saving adhesive, and in order to provide a means for holding down the strip a bottom flap 16 75 is projected substantially horizontal from the bottom edge of the same side from which the flap 11 projects, and is provided with perforations 17, and the adhesive, on which the strip is placed, passes through these perforations, and thus, when it dries, binds the strip down, assisting in this way the frictional engagement of the ridge 14 by the side wall 15, or if the strip is removed from 80 the side wall, as in holding down the edge 85 of a runner, the adhesive will suffice.

As shown in Figures 1 and 4, the bottom flap 16 can be also made imperforate, in which case it simply acts to rest on the floor, and acts, in conjunction with the flap 11, to 90 form a recess to receive the linoleum 12, and also acts as a top covering if the strip is to be used upside down as the edge or binding for a runner or for an otherwise exposed edge of a strip of linoleum or oil 95 cloth.

The modification shown in Figure 3 shows the edge opposite that from which the flap 11 projects as under-cut or recessed, as at 18. When this strip is used, cement is 100 placed at the juncture of the floor and the side wall and then the strip is pushed down in this juncture, thereby compressing the cement, as at 19, so that it fits in the juncture and is squeezed into the groove or recess 18, 105 and when the cement hardens the strip is held down.

In Figure 5 I show a modification in which the flap 16 is omitted and the floor covering 12 rests on the floor, and then the 110

strip 10 is pushed down so that the ridge 14 binds against the side wall 15 and thus acts to hold down the floor covering.

With this device an uneven edge is not in view and the strip thus adds to the appearance of the floor, and the laying of the floor covering is facilitated, because after an approximate fit of the linoleum to the room, the strip 10 is placed on the edge of the linoleum, then the linoleum and the strip are pressed down together so as to squeeze the strip into the position shown in Figure 2, and the laying is then complete.

I claim:

- 15 1. A strip for holding the edges of floor covering, said strip having a thin flap on the top of one edge, and a downwardly and inwardly inclined face on the other edge.
- 20 2. A strip for holding the edges of floor covering, said strip being made of flexible material and having an upwardly inclined pointed ridge on the top of one edge, and a thin flap on the top of the other edge.
- 25 3. A strip for holding the edges of floor covering, said strip having two flaps extending from one edge so as to grasp the edge of the floor covering, and having its other edge formed to provide an obliquely

projecting ridge, said ridge being adapted to bind against a side wall on an upward 30 tendency of the strip.

4. A strip for holding the edges of floor material, said strip having one edge provided with a resilient flap to receive the floor covering between them, and having a groove 35 in the other edge and below the top surface thereof.

5. A strip for holding the edges of floor material, said strip having one edge adapted to hold down the floor covering and having the other edge provided with a groove, said latter edge being adapted at its top to engage a side wall, and the groove being adapted to receive cement.

6. The method of laying floor covering 45 comprising the provision of a strip to receive the edge of the floor covering and having a recessed portion, placing cement at the juncture of the floor and side wall, and then pressing said strip in said juncture so that 50 said recessed portions receive cement.

In testimony that I claim the foregoing, I have hereto set my hand, this 26th day of January, 1922.

MARCUS PATTERSON.
